UNITED STATES PATENT OFFICE.

CHARLES J. KLEIN, OF MILWAUKEE, WISCONSIN, ASSIGNEE TO THE CUTLER-HAMMER MFG. CO., OF MILWAUKEE, WISCONSIN, A CORPORATION OF WISCONSIN.

ELECTRIC SWITCH DEVICE AND RECEPTACLE.

1,143,206.

Specification of Letters Patent. Patented June 15, 1915.

Original application filed April 28, 1911, Serial No. 623,903. Divided and this application filed October 5, 1911. Serial No. 653,036.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switch Devices and Receptacles, of which the following is a full, clear, concise; and exact description, reference being had to the accompanying drawing, forming a part of this specification.

My invention relates to electric switch devices and receptacles therefor.

It has among its objects to provide an 15 improved electric switch device.

A further object of my invention is to provide improved means for supporting and insulating a switch mechanism as well as improved means for inclosing the same.

20 Other objects and advantages of my improved construction will hereinafter appear.

In the accompanying drawings I have illustrated one form which my invention may assume in practice. My invention is, 25 however, not limited to this specific form shown for purposes of illustration but may assume other forms.

In the views of these drawings, Figure 1 shows a central sectional view of the switch 30 device in position in the socket. Fig. 2 shows a top plan view on line 2—2 of Fig. 1. Fig. 3 shows a side elevation of the socket with a portion of the cap broken away. Fig. 4 shows a top plan view of one 35 of the base members. Fig. 5 shows a bottom plan view of the same.

This application is a division of my co-pending application, Serial No. 623,903, filed April 28th, 1911.

40 In the construction illustrated in the drawings I have shown a push button operated switch mechanism of the type shown in this co-pending application. As described in that application, this switch mechanism 45 includes reciprocable push buttons 1 carried upon the ends of a central cam member 2 having oppositely disposed cam surfaces 3 upon its opposite sides. This cam member is arranged to reciprocate between the 50 parts 4 and 5 of an insulating base and actuates an oscillating movable contact member 6 provided with bearing surfaces 7 arranged to engage the active surfaces of the cams. The oscillating contact member 6 is 55 spring-pressed by a suitable spiral spring

8, surrounding a central shaft 9 which passes between the cams 3 of the cam member and serves to hold the parts of the base together by suitable taps 10 and 11 carried upon its ends. This specific form of switch 60 mechanism, however, constitutes no part of the present invention. Obviously, various other forms of switch mechanism may be employed in lieu of the same.

The insulating base is of substantially 65 cylindrical uniform cross section and its parts are so recessed as to provide a central chamber 12 within which the switch mechanism is housed. Communicating with this chamber 12 are suitable grooves 13 in the 70 adjacent parts of the base, through which the push buttons 1 are reciprocated. Suitable recesses 14 and 15 are provided in the upper and lower surfaces of the parts of the base to receive the taps 10 and 11. The terminal contacts for the switch mechanism are 75 preferably carried upon the upper surface of the part 5 of the insulating base. The contacts 16 and 17 are preferably of resilient type attached to the base by means of suitable screws or rivets 18 and 19 which extend through to the opposite side of the base, one of the same serving as a binding screw for the conductor, while the other is connected to a threaded shell 20 carried on the lower 80 surface of the part 5. In a preferred construction, the threaded shell 20 is provided with inturned portions 21 on its opposite sides which are substantially elliptical in shape and are housed in correspondingly 85 shaped recesses in the bottom of the part 5 and are located opposite each other. As previously mentioned, one of these parts 21 is connected to one of the resilient contacts 90 16—17. The other of these inturned portions 21 is attached to the base by means of a suitable screw 22. In a preferred form the central contact 23 is attached to the base by means of a suitable binding screw 24 which extends through to the upper surface of the 95 part 5 wherein its upper end is housed in a suitable recess. The bottom of the part 5 is preferably recessed to permit the neck of the central contact to pass through the same and the bottom of this part is also preferably 100 provided with a substantially star-shaped series of projections 26 which serve as 105 supports separating the conducting parts carried upon the bottom of part 5.

The part 4 of the insulating base, as pre- 110

viously described, is mounted upon the part 5 so that the grooves 13 in the bottom surfaces of the same register with the grooves 13 in the top surface of the part 5 in order 5 to permit the push buttons to pass through the same. In a preferred form, vertically extending conductor guiding grooves 27 are formed upon opposite sides of the two base members 4 and 5 so that the conductors may 10 be brought down along the side of the same to one of the contacts 16-17 and to the binding post for the central terminal 23. In order that the insulating base may be supported in a socket, the upper member 4 is 15 provided on its opposite sides with extensions 28. These extensions are provided with angularly disposed side walls 29 and beveled ends 30. In a preferred form these extensions 28 are preferably located above 20 the push buttons 1 and are slightly angularly disposed with respect to the same, as shown in Fig. 2.

The switch mechanism when inclosed in the two parts 4 and 5 of the insulating base 25 is carried in an improved socket. The socket is shown in section in Fig. 1. This socket is substantially cylindrical in cross section and is made in two parts 31 and 32, the part 31 constituting the body portion of the 30 socket while the part 32 constitutes the cap. In a preferred form the part 31 is formed of a single piece of punched metal and is provided with reinforcing ribs or beads 33 and 34 at points adjacent its ends. In a preferred form an insulating lining 35 of substantially cylindrical cross section throughout its length is carried within the part 31 of the socket and is held in position in the same by pressing a portion of the insulating 40 material into one of the beads or ribs 33-34. This insulating lining may be made of any suitable insulating material, such as a fiber if desired. As shown in Figs. 1 and 3 the upper end of the part 31 of the socket is 45 provided with oppositely located, vertically extending slots 36, which are rounded at their bottoms and arranged to receive the push buttons 1. The upper ends of these slots 36 are preferably cut away at one side, 50 as shown in Fig. 3, to form substantially rectangular-shaped openings above the push buttons which are adapted to receive the extensions 28 on the part 4 of the insulating base, as shown in Fig. 3. As illustrated in 55 Figs. 1 and 3, the insulating lining 35 is cut away opposite the openings in the top of the casing 31 and the bottom and side edges of the extension of the slot 36 are inturned, as 60 at 37, to prevent the rotation of the lining within the shell.

The upper member 32 of the shell or socket is in the form of a cap and is preferably provided with an outer metallic casing 65 having an insulating lining 38, and carries a threaded conductor nipple 39 on its upper

end. Within the nipple 39 a suitable threaded conductor bushing 40, having a central groove 41 through which the conductors extend to the switch mechanism, may be secured by a pin 42. As illustrated in Fig. 1, 70 the outer metallic casing 32 may be provided with a central opening which is adapted to receive the lower end of the nipple 39 and the nipple 39 may be provided with internal screw threads 43 arranged to receive the 75 bushing 40. In a preferred form the insulating lining 38 is locked in position within the cap 32 by means of one or more struck-in portions 44 in the body of the cap 32, preferably rounded out about a slit formed 80 in the cap. These struck-in portions are arranged to be received in suitable cut-away portions in the downwardly extending edges of the insulating lining 38. It is to be noted that the insulating lining 38 is provided 85 with a central opening at its top which registers with the groove in the insulating bushing 40 so that the conductors are fully insulated from any of the parts of the casing.

In order that the two parts 31 and 32 of 90 the socket or shell may not be rotated relatively with respect to each other, the adjacent ends of the same are preferably made polygonal in cross-section, as shown in Figs. 2 and 3. In the case of the upper cap member the cross section is a trifle enlarged in order that the cap may pass over and inclose the top of the part 31. In order that the two parts 31 and 32 of the socket may not be accidentally separated longitudinally, a flange 45 is formed on the cap 32 above the polygonal edge of the same, and one or more suitable struck-up portions 46 are provided on the polygonal portion of the part 31. As illustrated in Fig. 3 these struck-up portions are preferably provided with a rounded upper surface which is pressed outward, the lower edge of the struck-up portion being substantially straight where the metal of the part 31 is slit. These struck-up portions 46 are arranged to snap over one of the inner walls of the flange 45 when the parts of the socket are assembled, as shown in Fig. 1 and thus effectually prevent any accidental longitudinal separation of the parts of the casing. However, when it is desired to separate these parts they may be very readily separated by simply depressing a portion of the part 31 adjacent the 100 polygonal portion, as, for instance at the point indicated by an arrow in Fig. 3.

By my improved construction I have provided an improved electric switch device which is adapted to use with any one of a large number of electric switch mechanisms. The switch mechanism is compactly housed between the parts of an insulating base which carries all the terminal connections for the same and when assembled constitutes a single unitary mechanism which may be readily 105 110 115 120 125 130

removed from the casing by simply pushing the same out of one end of the casing. Further, by my improved construction, this base in its inclosed switch mechanism is supported by the casing and insulated therefrom and is prevented from rotating within the casing. By the provision of my improved construction and arrangement of terminal connections for the switch mechanism, these parts are effectively insulated from each other and are very conveniently arranged so that the conductors may be readily attached to the same when desired. By the improved construction of the casing which I have employed I have been able to provide a casing of substantially cylindrical uniform cross section which may be readily and cheaply manufactured and which may be constructed in a very small size. Further, all of the parts of the switch mechanism are effectively insulated from this casing and the linings within the casing are so attached to the casing that they may not move independently of the same. Further, by my improved construction the two parts of the casing are prevented from rotating with respect to each other and from being accidentally separated longitudinally while they may be very readily separated when it is desired to separate them and may be readily assembled by simply snapping the two parts together. Further, by my improved construction and arrangement of the parts herein described I am able to provide an electric switch device which may be manufactured in a very compact form so as to occupy but little space and which is of a rugged construction well adapted to stand long use and service and capable of being manufactured at small expense.

While I have in this application described one specific form which my invention may assume in practice I do not wish to be limited to this specific form but wish rather to include all of those modifications and adaptations of my invention which fall within its spirit.

What I claim as new and desire to secure by Letters Patent of the United States is:—

1. In a lamp socket, in combination, a switch mechanism having a rigidly protruding operating member, a supporting base for said switch mechanism having a laterally extending projection above said operating member, a two-part inclosing casing for said base having an open-ended slot to receive

said operating member and said projection and having transverse walls engaging said projection to support said base.

2. In a lamp socket, in combination, a base for the current carrying parts provided with laterally extending supporting lugs and a two-part casing for said base having open-ended slots in one part thereof to receive said projections of said base, said projections engaging with bottom walls of said slots to support said base within said casing and engaging with side walls of said slots to prevent rotation of said base relative to said casing.

3. In a lamp socket, in combination, a switch base having laterally extending portions providing transverse and longitudinal shoulders, and a two-part inclosing casing for said base having open-ended slots to receive said projections, the side and bottom walls of said slots being inturned to engage the transverse and longitudinal shoulders of said base to support the same and to prevent rotation thereof relative to said casing.

4. In combination, a switch mechanism having oppositely disposed push-buttons, a supporting base therefor, said base being provided contiguous to said push-buttons with lateral projections and an inclosing casing for said switch and said base comprising two telescoping sections, one having slots on opposite sides to receive said projections of said base and having communicating slots to receive said push-buttons, said projections of said base engaging the walls of said first mentioned slot to support said base and prevent rotation thereof relative to said casing.

5. In combination, a switch having a push-button operating member, a supporting base therefor having a shoulder and a two-part inclosing casing for said switch and base, one part of said casing having an open-ended slot at one end thereof to receive said push-button and having a shoulder to engage said base shoulder for supporting said base in position with said pushbutton out of contact with the walls of said slot.

In witness whereof, I have hereunto subscribed my name in the presence of two witnesses.

CHARLES J. KLEIN.
